[57] CLAIM

The ornamental design for a loudspeaker, substantially as shown and described.

DESCRIPTION

FIG. 1 is a front elevation of the loudspeaker showing my new design;

FIG. 2 is a rear elevation thereof;

FIG. 3 is a top plan view thereof;

FIG. 4 is a side elevation thereof;

FIG. 5 is a bottom plan view thereof;

FIG. 6 is a front elevation of a modified embodiment of the loudspeaker illustrated in FIG. 1;

FIG. 7 is a rear elevation thereof;

FIG. 8 is a top plan view thereof;

FIG. 9 is a side elevation thereof; and

FIG. 10 is a bottom plan view thereof.

Fig.1.

Fig.2.

Fig.3.

Fig. 4.

Fig. 5.

FIG. 9

FIG. 10
